DRAFT APPLIANCE FOR FURNACES

Filed July 28, 1930

FIG. 1.

FIG. 2.

FIG. 3.

INVENTOR

Arthur J. Reed

BY

George J. Chancles

ATTORNEY.

WITNESS:

Pete R. Kitchel.

UNITED STATES PATENT OFFICE

ARTHUR J. REED, OF PHILADELPHIA, PENNSYLVANIA

DRAFT APPLIANCE FOR FURNACES

Application filed July 28, 1930. Serial No. 471,127.

My invention relates to a draft appliance for furnaces and has for its object to provide a draft appliance connected with and incorporating a closure plate to an ash pit door and so constructed as to provide for its convenient withdrawal from its operative position in connection with the furnace and for the firm closing of the ash pit door when the appliance is in operative position.

10 The nature of my improvements will be best understood as described in connection with the drawings, in which

Figure 1 is a plan view showing a portion of the furnace in horizontal section taken 15 through the ash pit door opening and my appliance in the position it occupies when the closure plate is brought against the ash pit door opening but not yet clamped against the doorway.

20 Figure 2 is a side elevation of the parts and mechanism shown in Fig. 1, viewed from the left hand side of that figure, and

Figure 3 is a front elevation of the same parts.

25 A indicates the furnace having an ash pit doorway, as indicated at A¹. B is the pivotal support adapted to be secured to the floor of the room in which the furnace is located at some distance from the furnace and having as shown a pivot pin, indicated at B¹. Pivoted on this support is the head indicated at C, upon which is supported a motor D and a fan E, driven by the motor. The pivoted head also supports a laterally extending arm, 30 indicated at F, which rotates with the head and which is formed or provided with spaced lugs F¹ F¹ longitudinally slotted as indicated at f¹ and also at its end with a lug F². G, G are cross bars formed as shown with transversely extending slots g. These cross bars G are secured to the arm F by means of set screws P, which are vertically adjustable in the slots f¹ of the lugs F¹ and on which the cross bars G are adjustable along the length 35 of the arm F.

40 In this way I provide for both a vertical and transverse adjustment of the bars G and the parts carried thereby including the closure plate to secure to the ends of the cross bars G, which frame is made up of 45 a portion G¹ running parallel to the cross bars

G and having laterally extending arms G² which are slotted to permit of adjustment as indicated at g² and which when adjusted are secured to the ends of the bars G by clamping screws indicated at Q. H indicates the 55 ash pit closure plate, which is supported on the arm F through the plates G and G¹ by pins I, I, etc., secured to the back of the closure plate and extending through perforations in the plates G and G¹. J, J, etc. are 60 springs surrounding the pins I and located between the closure plate and the plate G¹. K, K¹, K² indicate an air conduit connecting the fan E with the ash pit closure plate H, and opening through said plate. This conduit is 65 shown as incorporating a flexible section indicated at K². L, L¹ indicate toggle links of which the link L is pivotally connected at l to the lug F² extending out from the arm F and pivotally connected at l¹ with the link 70 L¹, the end of which is formed to make a ready engagement with the stop M secured to the floor of the room and preferably 75 formed as a ratchet, as shown. The link L¹ is provided with a finger L² to engage the link L when the toggle is straightened out and the link L is provided with a handle as indicated at N. O, O¹ is a bent lever pivoted to the link L and carrying at its free end a hook, as indicated at O², adapted to engage 80 with an extension F³ of the arm F. This bent lever is provided with a lever extension O³.

85 In installing my apparatus in connection with a furnace the base plate B is secured to the floor of the furnace room at a proper distance and at a proper angle to the furnace to provide for the closing of the closure plate H against the ash pit door opening. The ratchet detent M is also secured to the floor of the furnace room at a proper distance to be engaged by the toggle lever when the closure plate is in operative position, the framing G, G¹, G² which supports the closure plate is then adjusted on the arm F, if necessary, 90 to bring the closure plate into proper registry with the ash pit door opening. To bring the appliance into operative position it is brought up against the ash pit door opening, 95 as shown in Fig. 1, the toggle lever L¹ is en- 100

- gaged with the ratchet detent M and the toggle straightened out so that it exerts a forward push on the arm F and through the plates G¹ secured to the arm F pressure is exerted against the springs J, with the result that the door is firmly clamped against the rims of the ash pit door opening and the appliance is in full operative position for delivering air to the furnace ash pit.
- 10 When it is desired to open the ash pit doorway it is only necessary to lift the toggle as by its handle N and pull it up to a position in which the hooked end O² of the bent lever O, O¹ will engage the detent F³, the effect of which is to hold the toggle levers up in inoperative position so that the whole appliance can be swung away, giving full access to the ash pit.

When the appliance is again brought back to position in which the closure fits against the ash pit doorway pressure on the arm O³ will lift the hook from engagement with the detent and permit the toggle link L¹ to engage the detent M preparatory to a clamping 25 of the closure plate in operative position. It will be observed that my described construction provides not only for an adjustment of the closure plate through an adjustment of the frame G, G¹, G² on the arm F, but also 30 provides for a free angular adjustment of the closure plate on the ash pit door rim by reason of the fact that the springs J make such an angular adjustment practicable.

The construction which I have illustrated 35 and described is, I believe, the best embodiment of my invention but is capable of modifications without departing from the spirit of my invention.

Having now described my invention, what 40 I claim as new and desire to secure by Letters Patent, is:

1. A draft appliance for furnaces comprising a pivotal support, a head rotatively supported thereon and supporting a motor 45 and fan, a laterally extending arm secured to and rotated with the head, an ash doorway closure plate adjustably supported on said arm, an air conduit connecting the fan and closure plate and opening through said plate 50 and means for clamping the plate against an ash pit doorway.

2. A draft appliance for furnaces comprising a pivotal support, a head rotatively supported thereon and supporting a motor 55 and fan, a laterally extending arm secured to and rotating with the head, an ash doorway closure plate adjustably supported on said arm and spaced therefrom by compressible springs, an air conduit connecting the 60 fan and said plate and opening through said plate, and clamping mechanism acting on the arm and through the springs to secure the plate against an ash doorway.

3. A furnace draft appliance as called for 65 in claim 2 in which the clamping device con-

sists in a toggle, one link of which is pivotally connected to the arm and the other link of which is adapted to engage with a detent on the floor.

4. A furnace draft appliance as called for in claim 2 in which the clamping device consists in a toggle one link of which is pivotally connected to the arm and the other link of which is adapted to engage with a detent on the floor, said toggle links being provided with a latching device for holding them in non-operative position.
